UNITED STATES PATENT OFFICE.

ABRAHAM STONE, OF BROOKLYN, NEW YORK.

GARMENT BAG.

Application filed May 1, 1924. Serial No. 710,245.

To all whom it may concern:

Be it known that I, ABRAHAM STONE, a citizen of the United States, residing at Brooklyn, in the county of Kings, city and State of New York, have invented certain new and useful Improvements in Garment Bags, of which the following is a specification.

This invention relates to improvements in garment bags and more particularly to improvements in supporting hooks for moth-preventive bags.

The particular object of the invention is to provide a supporting hanger which will be economical to manufacture and which at the same time can be adjusted in any plane with reference to the plane of the garment bag, unlike the present hangers employed on this variety of garment bags.

Further objects of the invention will be apparent from the drawing, in which—

Figure 1 shows in perspective a garment bag equipped with one of my improved hangers,

Figure 2 is a side view of said bag and hanger showing the hook held in a plane parallel with the body of the bag, and

Figure 3 is a side view of the bag and hanger showing the hook held at right angles to the body of the bag.

1 designates a paper moth-preventive garment bag of the usual construction and 2 my improved hanger which is constructed in the following manner:

35 The hook 3 is swivelled in the metallic sleeve 4 so that the hook 3 can be rotated at any angle. This is an important advantage with this style of hanger because usually these hooks are rigidly fastened to the sup-

porting members and so the bag can only 40 be supported in a fixed relation with the plane of the hook. In this case, owing to the swivel connection of the hook with its supporting members, the hanger can be held in any position with relation to the bag as 45 is shown in Figures 2 and 3. The sleeve 4 is loosely held by and rotatably mounted in the rectangular holder 5 whose ends are fixed in the collar 6, an extension of which forms the plate 7 which is directly fastened to the 50 body of the bag 1 by means of the teeth 8 struck up from the body of said plate.

I am aware that in its general form this hanger is old and well known in the art but what I claim in my particular invention is 55 the mounting and support of the hook by which it may be rotated or hung in any plane with reference to the position of the garment bag itself.

Having thus fully described my invention, 60 what I claim is:—

In combination, a garment bag having a plate connected thereto, the upper end of said plate being inturned, a hook carrier comprising a substantially rectangular member passing through the inturned end of said plate so as to be revolvably supported, the said hook carrier having an upwardly bent portion in the upper part thereof, a sleeve loosely connected to said carrier at 70 the said upwardly bent portion of the upper end thereof, and a hook revolvably connected to said sleeve, said hook being adapted to turn about an axis perpendicular to said sleeve.

In testimony whereof I hereunto affix my signature.

ABRAHAM STONE.
